UNITED STATES PATENT OFFICE.

SIGMUND FECHHEIMER, OF NEW YORK, N. Y.

SHIRT AND NECKTIE FASTENER.

SPECIFICATION forming part of Letters Patent No. 310,661, dated January 13, 1885.

Application filed October 23, 1884. (No model.)

To all whom it may concern:

Be it known that I, SIGMUND FECHHEIMER, of the city, county, and State of New York, have invented a new and Improved Combined 5 Shirt and Necktie Fastener, of which the following is a full, clear, and exact description.

The object of my invention is to produce a cheap, simple, and easily-applied clasp, of any desired ornamental configuration, the same 10 being constructed to form a combined shirt and necktie fastener capable of being used both for closing and fastening the opening neck and bosom portions of a shirt and for receiving through it and holding the ends of 15 a necktie or scarf, arranged when in position to lie or fall down the center of the bosom of the shirt. By means of my improved device, constructed substantially as hereinafter described, I am enabled to dispense with 20 studs or buttons for closing the shirt in front, and to provide the shirt with simple button holes or eyelets for the purpose, thus doing away with a great annoyance—as when, for instance, buttons are lost from the shirt by 25 washing or otherwise—and the device at the same time serving to form an ornamental clasp for the ends of the tie or scarf at the neck, or at any number of fixed points down the bosom of the shirt, and to allow of said 30 ends being entered or removed with the same facility as an ordinary scarf-ring affords, thus virtually forming both a button substitute for shirts and a scarf ring or clasp, and as such constituting a new and useful article of manu- 35 facture. By means of this improved device the shirt, scarf or necktie, and fastener are all combined and connected to make of the whole one article.

Reference is to be had to the accompanying 40 drawings, forming a part of this specification, in which similar letters of reference indicate corresponding parts in all the figures.

Figure 1 represents a front view of a shirt with my improved device, under different ornamental forms or shapes, applied, and showing the ends of a necktie or scarf as partly inserted through said devices. Fig. 2 is a longitudinal section upon a larger scale of the device in one of the forms shown in Fig. 1 de-

tached, and Fig. 3 a back or inner face view 50 thereof.

The whole device is made of metal struck up or otherwise fashioned to form a widened or spread face-piece of any desired design, and hooks of narrower construction on or from 55 opposite ends of said face plate or piece, arranged to bend inward toward one another at the back of the face-piece, and at such a distance from the latter as to admit of the falling ends or portions of a necktie or scarf freely 60 passing down in between the back or back edges of the face-piece and the inner faces of the hooks or fastenings.

Fig. 1 of the drawings shows three different patterns of the clasp applied to the front 65 of a shirt, A—that is to say, a clasp, B, having its face-piece *b* and end hooks or fastenings *c c* made of one and the same piece of sheet metal, such as is shown applied to secure the neck portion of the shirt—the face-piece of said clasp being of ornamental or brooch-like configuration; a lower fastening or clasp, B', having a face-piece, *b*, of buckle-like configuration, with its center bar extended and bent backward and inward to form opposite end hooks or fastenings, *c*, that stand away from the back of the face-piece; and a still lower shell-like clasp, B'', having its face *b* supported and stiffened at its back by a band or strip soldered or otherwise secured 70 to it, and arranged to extend across or along it, and bent at its ends to form the hooks *c c*, as more clearly shown in Figs. 2 and 3. Regardless of the precise form or ornamental configuration of the clasp, however, the face 75 piece or portion *b* is in every case of a widened or spread configuration, and the hooks *c*, which it is preferred to make blunt at their ends, are of a much narrower construction than the face-piece, and are set back sufficiently from said 80 face-piece to form or leave an open space, *s*, between it and them. Clasps or fasteners thus constructed may not only be used to close and fasten or hook together the opening at the neck and down the bosom of the shirt by passing the hooks *c* of the clasp through eyelets or button-holes *d* in the shirt on opposite sides 85 of said opening, but a scarf or necktie, *C*, after

having been passed round the neck and under the collar of the shirt, may have its falling or pendent ends secured in position by passing them through the spaces in the clasp, between

5 the hooks and back of the face-piece, with every freedom of adjustment as regards the tie, and allowing of the ready entry and removal of the ends thereof through the clasp, which not only holds the necktie in place between the front of the shirt and back of the face piece or plate, but also fastens the edges of the shirt-bosom securely together.

10 This device essentially differs from a device for attaching neckties to collars, made of wire or sheet metal, having no enlarged or ornamental face-piece, but made of a piece of wire or strip of sheet metal of uniform width, with its ends bent into sharp-pointed hooks of like width as the rest of the structure, for catching into or penetrating the collar and admitting of the necktie being drawn back and forth in a circular direction through them. It also essentially differs from a mere garment supporter or fastener formed of a piece of wire

15 or sheet metal the ends of which are bent 25 close or nearly close back upon itself, and the extremities of such bent portions bent outward to form V-shaped openings.

20 Having thus fully described my invention, I claim as new and desire to secure by Letters 30 Patent—

25 As an improved article of manufacture, a shirt and necktie fastener made as herein shown and described, the same consisting of 35 a face-piece provided with inwardly-bent end hooks or fastenings that stand away from the back of the face-plate, so as to leave space when applied to the shirt for the necktie, and hold the same in place between the front of the shirt and the back of the face plate or 40 piece, while at the same time the edges of the shirt-bosom are securely fastened, all as set forth.

SIGMUND FECHHEIMER.
